UNITED STATES PATENT OFFICE

CARL C. CHITTIM, OF SPRINGFIELD, MISSOURI

FOLDABLE BED CONSTRUCTION

Application filed April 1, 1927. Serial No. 180,311.

This invention relates to a foldable or collapsible bed, and more particularly to a construction of bed that may be placed within an automobile so that the occupants may sleep within the car without in any way being subject to inconvenience.

An object of the invention is a construction that can be neatly and substantially supported upon the seats of an automobile and in such a manner that entrance and exit from the car is not interfered with.

Another object of the invention is to incorporate into the construction extensible features so that the bed may be used for a plurality of purposes.

Another object of the invention is the novel manner of cutting and arranging the bed bottom so that upon extension of the various parts to set-up position the bed bottom will be tensioned to the required amount to properly and comfortably support an occupant.

Besides the above, my invention is distinguished in the simple, substantial manner in which the various parts are connected for extensible and foldable movements, and when in extended position all parts are rigidly placed under strains to hold the bed bottom properly stretched and to prevent accidental disengagement between the various connections.

With these and other objects in view, my invention will be better understood from a description of the accompanying drawings, wherein:

Figure 1 is a side elevation of the bed shown in applied position;

Figure 2 is a top plan view;

Figure 3 is an enlarged side elevation;

Figure 4 is an enlarged end elevation;

Figure 5 is a bottom plan view showing the parts collapsed;

Figure 6 is a sectional view through one of the legs;

Figure 7 is a perspective view of a portion of the brace bar and a portion of the leg associated therewith;

Figure 8 is an enlarged end elevation of the bed with one of the legs collapsed;

Figure 9 is a cross sectional view;

Figure 10 is a detail sectional view of one of the legs;

Figure 11 is a longitudinal sectional view of the head end of the cover;

Figure 12 is a similar view through the foot end of the cover.

Again referring to the drawings, the numeral 1 designates the main section comprising the longitudinally extending side bars 2, to the ends of which are connected the hinges 3.

The side bars also have pivotally connected thereto the hinge elements 4 that provide the pivotal connections between the side bars and the extensible legs 5. Each leg 5 includes an upper section 6 and a lower section 7 adjustably connected together by the pivot pin 8 so that the lower section may be folded into parallel relation with the upper section, and for the purpose of holding the sections in extended position the lower section 7 carries a U-shaped clip 9

adapted, when moved into one of its positions, to interlock or straddle the upper section 6, and thus in a very simple, inexpensive manner the leg sections are connected together

for collapsible or extensible movement and when in an extended position the parts are rigidly connected together to assure the substantial support of the bed. The leg structures are connected together in pairs by the

brace bars 10 arranged between and having abutting relation with the legs so as to not only spread the legs apart properly but exert pressure in a direction that the engagement

between the brace bar and the legs is more effective and accidental dislocation positively prevented. To accomplish this desired result, the ends of the brace bar are provided with pins 11 seated in sockets 12 in the legs.

Associated with the main section are the end sections 13 and 14, which are of identical construction, consisting of the side bars 15, the inner ends of which are connected to the

hinges 3 and the outer ends provided with pins 16 seated in sockets 17 in the cross bars 18. It will now be appreciated that with the side bars and brace bars in position, the end bars and side bars will be properly spaced

to properly tension the bed bottom 19 that is secured thereto.

The bed bottom 19 is an important part of my invention and is lapped part way around and secured to the side bars, as at 20, and end bars by tacks or other elements and further provided with end loops 21 for receiving the 5 end cross bars, and thus it will be appreciated that the bed bottom will be effectively tensioned in a transverse direction by the pressure exerted against the side bars and end 10 bars and will be effectively tensioned in a longitudinal direction in the swinging movement of the end sections toward set-up position. This bed bottom has a longitudinally extending reinforcing web 22, to one end of which, and to the corresponding end loop 21 15 of the bed bottom, is secured an adjustable strap 23, and thus the initial tension of the bed bottom may be regulated so that the end sections may be allowed to properly move to 20 extensible position and be held in such position by the tension of the bed bottom. This bed bottom is provided with recesses 24 to avoid contact of the bottom with the hinges 3 and 4 and further cut away to provide a 25 rectangular opening 25 adjacent one corner of the bed to allow the passage therethrough of the steering wheel 26 of the automobile, straps 28 being provided to straddle the wheel and properly support that portion of the bed bottom 30 arranged adjacent the steering wheel.

To complete the structure, braces 29 and 30 connect the cross brace bars 10 to the legs, with one of the braces detachably secured to the leg, as indicated at 31, so that one end of 35 each brace bar may be completely detached from a leg to allow the proper folding of the parts, as indicated in Figure 5.

By referring to Figure 5, it will be noted that the legs 5 may be arranged in a collapsed 40 position and swung into parallel relation with the under surfaces of the side bars 2 associated therewith and the bars 15 folded in parallel relation with the upper surfaces of the side bars 2 and thus I provide a very compact 45 arrangement of the parts so that in the rolling of the bed bottom the parts will be concealed therein. Of course, it is to be understood that previous to the rolling of the bed bottom the end bars 18 have been removed 50 and placed upon the cover, as indicated in broken lines in Figure 5.

The foldable features of the bed are such that a very compact bundle is provided and when the bed is to be set up it is only necessary to place the end bars 18 in interlocking engagement with the ends of the bars 15 for completing the frame and then swinging the brace bars 30 into interlocking engagement with the legs for completing the setting up of 60 the bed. Thus in two simple operations I am able to either collapse or set up the bed, and when in a collapsed condition the same will occupy a minimum amount of space and when in a set-up position all parts are substantially 65 connected to provide a rigid substantial struc-

ture with the legs extending in a position to rest upon the cushion boards of the car after the cushions have been pulled forward sufficiently and the legs are of a sufficient length to hold the bed frame above the front seat back of any design of car.

In concluding, I wish to emphasize the economical manner in which each part is constructed and the relatively few parts necessary in the construction of the bed that not only materially reduces the number of machine operations but materially reduces the cost of assembling, thereby materially reducing the manufacturing cost of the article as a whole.

It is, of course, to be understood that changes may be made in the manner of constructing certain parts of the invention without departing from the spirit of the invention and, therefore, I do not desire to be limited in any manner except as set forth in the appended claim.

I claim:

In a foldable bed structure of the class described, a main section including side members, end sections including side members foldably connected with the side members of the main section, cross bars extending between and separably connected at their ends with the side members of the end sections, a bed bottom stretched to extend between all of said side members and the cross bars, pairs of legs foldably connected at their upper ends with the side members of the main section, a cross bar disposed to extend between the legs of each pair, each leg of each pair having a socket in its inner side, the cross bar being provided at its ends with studs removably engageable in said sockets and separably connecting the cross bar with the legs, and braces pivotally connected to each of the cross bars and extending diagonally to the adjacent legs, one of said braces being also pivotally connected to the respective leg and the other brace being separably connected with the other leg.

In testimony whereof I affix my signature.

CARL C. CHITTIM.
